BOILER

Robert L. Byrum, Middletown, Ohio

Application December 16, 1938, Serial No. 246,220

4 Claims. (Cl. 122—166)

This invention relates to water boilers and more particularly to the type of steam generators or water heaters for domestic hot water or steam heating systems or domestic hot water supply systems.

It is the object of the present invention to provide a water boiler which is compact and rugged in construction, highly efficient in operation and capable of developing the desired temperatures for utilization within a relatively short period of time.

It is a further object of the invention to provide a boiler having maximum heat transfer area while obtaining optimum draft conditions.

It is a further object of the invention to provide a boiler construction which develops improved circulating characteristics in the liquid undergoing transformation, which contribute to the attainment of high efficiency and rapidity of operation.

The present invention proceeds upon the principle of the most efficient extraction of the heat of combustion gases developed by the ignition of fuel, which may be gaseous, liquid, vapor, solid particles or mixtures of these, by the interposition of tubes carrying the heated liquid medium into the path of these combustion gases, while the circulation of the liquid medium is maintained at optimum conditions in order to extract quickly the heat from the gases and to transfer the energy thus derived from the heated gases to the liquid at the point of utilization thereof. Thus, if water is used for the purpose of generating steam, the heated water is permitted to discharge near the point of production of steam, while in the case

the system is used merely for the heating of water, the heated water is discharged near the point of exit of the water from the boiler for utilization in other points of the heating system, as by radiation and the like. The inducement of the water to travel quickly following the absorption of heat thereby to the point of utilization and the immediate and simultaneous replenishment of the tubes with additional water having a greater temperature differential than the previously heated water, give rise to a maximum utilization of the heat energy of the fuel being utilized before the heated gases pass from the boiler. These objectives are attained in the present invention by the provision of a plurality of tubes

conveying the liquid being heated in the paths of the combustion gases and which in addition are provided with extensions within the main body of the liquid at one of the ends of the tubes to produce by conduction the desirable currents

of heated liquid rather than merely to rely upon the convection effects of the liquid medium of different temperatures in the liquid chamber.

The cross sections of the liquid or water tubes in the fire chamber, as well as in the liquid chamber are so critically proportioned and distributed that the conduction paths of the heated liquid are maintained at maximum efficiency while sufficient space is left for the convection currents of the liquid to abstract with maximum efficiency the heat from the combustion gases passing upwardly through the fire chamber and striking the inner lateral walls of the liquid jacket and the stack extending upwardly therefrom.

Other objects and purposes will appear from the more detailed description of the invention following hereinafter, taken in conjunction with the accompanying drawing, wherein:

Figure 1 is a vertical sectional view of my improved boiler;

Figure 2 is a horizontal sectional view along line 2—2 of Figure 1; and

Figure 3 is a horizontal sectional view along line 3—3 of Figure 1.

In Figure 1 is shown a boiler casing 1 of cylindrical external contour which may rest upon a base 27 in which may be disposed the burners 20 and 21. In the illustrated embodiment of the invention, the burners are shown consisting of four elements 20, with a central pilot burner 21, which are supplied with gaseous fuel from mains 22 and 24 respectively. It is understood that any other form of burner may be disposed in the base of the boiler adapted to burn fuel oil, coal, or any other combustible material.

The combustion flames and gases pass upwardly from the burner into a fire chamber F formed by lateral walls 3 and top wall 13 from utilization in other points of the heating system, as by radiation and the like. The inducement of the water to travel quickly following the absorption of heat thereby to the point of utilization and the immediate and simultaneous replenishment of the tubes with additional water having a greater temperature differential than the previously heated water, give rise to a maximum utilization of the heat energy of the fuel being utilized before the heated gases pass from the boiler. These objectives are attained in the present invention by the provision of a plurality of tubes

conveying the liquid being heated in the paths of the combustion gases and which in addition are provided with extensions within the main body of the liquid at one of the ends of the tubes to produce by conduction the desirable currents of heated liquid rather than merely to rely upon the convection effects of the liquid medium of different temperatures in the liquid chamber.

in the lateral jacket formed between the walls 3 and the external wall of the boiler. Thus, the tubes 16 extend upwardly from the ends of the tubes 6 while the tubes 17 extend upwardly from the ends of the tubes 7 opposite the ends of tube 6 to which the tubes 16 are attached. Likewise tubes 8 and 9, which extend at right angles to the tubes 6 and 7, have attached thereto upwardly extending tubes 18 and 19, respectively, on opposite sides of the fire chamber. The rows of water tubes 10 and 11 are disposed at right angles to each other and have no tubular extensions connected thereto, which is characteristic of presently known constructions. The tubes 16, 17, 18 and 19 extend beyond the height of the fire chamber and terminate below the level of the water in the boiler.

A discharge conduit 25 is connected to the top of the boiler for leading off steam from the boiler if the same is used for such a purpose which is the case in the illustrated embodiment of the invention. In the event that the present construction is used as a hot water boiler, it is filled with water and the conduit 25 leads away the heated water therefrom. The boiler may be provided with a level indicator 10, and whatever additional controls, such as a thermometer and a pressure indicator I, as are conventional in insulations of this type. An inlet conduit for the water is shown at 30.

Without limiting the present invention, it is the applicant's theory that the improved results obtainable with the design illustrated herein arises from the provision of the upwardly extending tubes 16, 17, 18 and 19, which rapidly convey the water heated in the horizontal sections of the tubes, 6, 7, 8 and 9, to the upper part of the main body of water wherefrom the water is conducted away, or else transformed into steam. The incoming cold water is directed into the bottom of the boiler through conduit 30 and fills the horizontal water tubes and which operates to extract the heat from the combustion gases. In addition, the cooler water travels downwardly in the lateral water jacket and fills the tubes 6, 7, 8 and 9, as well as 10 and 11, to heat the liquid therein. These currents of cooler water do not obstruct and are not obstructed by the hot water passing upwardly through the tubes 16 to 19. In addition, the hot combustion gases strike the wall or walls 3 and heat the water in contact therewith.

I have found a constructional design as set forth below and illustrated herein particularly efficient. The boiler casing is of 20" diameter and 36" height through which extends a fire chamber of 12" square cross section through the lower half thereof with a stack of 3" diameter extending upwardly therefrom and terminating 2" above the top of the boiler. The boiler rests upon a base 12" in height with air openings therein, which serves to give adequate draft from below. A water level of approximately 24" is maintained in the boiler for the purpose of steam generation and the tubes 16 to 19 terminate about 1 1/2" below this water level.

The tubes are 3/4" in diameter and set 1 3/4" from center to center and these are disposed midway between the fire chamber and the external jacket, which at the center is 4" in width. When the fire chamber is cylindrical or of any other curved outline, the water tubes are correspondingly curved in their substantially horizontal planes so that the ends of the tubes are perpendicular or substantially so to the plane of

the fire box at their points of juncture thereto by welding or brazing.

The low pressure steam generator or water heater described herein may be made of sheet metal or any other materials used in the art for these purposes. The water tubes may be fabricated of copper, brass, stainless steel or other suitable materials. In view of the high rate of heat absorption made possible by the improved construction disclosed herein, the capacities of the boiler are increased or correspondingly the size of the boiler may be reduced for the same capacities obtained heretofore.

The water tubes are so designed that a rapid circulation of water takes place therein by the aeration occasioned by the generation of steam in some of the water tubes. These rapid velocities of the water in the tubes may be sufficient to maintain these tubes clean. As a refinement, I may provide removable plugs at the ends of the horizontal water tubes at the bases of the vertical extensions to facilitate the cleaning of the tubes if such is necessary.

While my invention has been described as relating particularly to a water heating or steam generating apparatus, it is understood that "steam" and "water" as used in the specification and claims are capable of broader interpretations in order to connote any liquid and vapor produced therefrom so that the novel features of the present invention may be applied to other fields than that specifically disclosed herein.

While I have described my invention as embodied in concrete form and as operating in a specific manner for purposes of illustration, it should be understood that I do not limit my invention thereto, since various modifications will suggest themselves to those skilled in the art without departing from the spirit of my invention, the scope of which is set forth in the annexed claims.

What I claim is:

1. In a boiler of the class described, a fire chamber, a liquid chamber above and around said fire chamber, a plurality of adjacent pairs of rows of water tubes extending transversely of said fire chamber between opposite points in said water chamber, each pair of rows of tubes extending transversely to another pair of rows of tubes, and tubular extensions connected to said water tubes at the opposite ends of the rows of tubes constituting the pair thereof, said extensions directed upwardly for a substantial extent in said water chamber and terminating below the level of the water therein to conduct the water heated in the transverse portions of said water tubes to the upper part of the body of water in said water chamber.

2. In a boiler of the class described, a fire chamber, a liquid chamber above and around said fire chamber, a plurality of adjacent pairs of rows of water tubes extending transversely of said fire chamber between opposite points in said water chamber, each pair of rows of tubes extending transversely to another pair of rows of tubes, and tubular extensions connected to said water tubes at only one end thereof and directed upwardly for a substantial extent in said water chamber and terminating below the level of the water therein to conduct the water heated in the transverse portions of said water tubes to the upper part of the body of water in said water chamber, said tubular extensions being distributed in said liquid chamber by being connected to the ends of one row of tubes which are op-

posite the ends of the other row of tubes of the same pair to which other tubular extensions are connected.

3. In a boiler of the class described, a rectangular fire chamber, a liquid chamber above and around said fire chamber, inlet and outlet conduits connected thereto, a plurality of adjacent pairs of rows of water tubes extending transversely of said fire chamber between the opposite walls thereof and openings into said water chamber, each pair of rows of tubes extending transversely to the adjacent pair of rows of tubes, and tubular extensions connected to said water tubes at the opposite ends of the rows of tubes constituting the pair thereof, said extensions directed upwardly in said water chamber for a substantial extent to conduct the water heated in the transverse portions of said water tubes to the upper part of the body of water in said water chamber.
4. In a boiler of the class described, a fire

chamber, a water chamber above and around said fire chamber, a plurality of adjacent pairs of rows of water tubes extending transversely of said fire chamber between displaced points in said water chamber, each pair of rows of tubes extending transversely to another pair of rows of tubes, tubular extensions connected to said water tubes at the opposite ends of the rows of tubes constituting a pair thereof, said extensions directed upwardly for a substantial extent in 10 said water chamber to conduct the water heated in the transverse portions of said water tubes to the upper part of the body of water in said water chamber, additional water tubes extending transversely of said fire chamber and crossing each other above said first-mentioned water tubes, and a stack extending upwardly from said fire chamber through the upper part of the water chamber.

ROBERT L. BYRUM. 20
